ATTORNEYS

UNITED STATES PATENT OFFICE.

PERCY LEON BILLINGSLEY, OF ORLANDO, FLORIDA.

MORTISING OR SLOTTING DEVICE.

Application filed July 5, 1921. Serial No. 482,383.

To all whom it may concern:

Be it known that I, PERCY L. BILLINGSLEY, a citizen of the United States, residing at Orlando, in the county of Orange and State of Florida, have invented certain new and useful Improvements in Mortising or Slotting Devices; and I do hereby declare the following to be a full, clear, and exact description of the invention, such as will enable others skilled in the art to which it appertains to make and use the same.

The present invention relates to mortising and kindred devices, and aims to provide a novel and improved portable device of that kind adapted to be driven by a flexible driving mechanism, and intended especially for use as an attachment to the flexible operating mechanism disclosed in my copending application filed May 17, 1921, Serial No. 470,413 (Patent No. 1,424,148 granted August 1, 1922).

Another object is the provision of such a device comprising novel means for mounting and guiding an auger bit or equivalent tool, for making mortises or slots in window frame stiles, boards, and other objects, or for doing other similar work, provision being made for adjustments to regulate the length and depth of the mortise or slot, and the angles of the end walls thereof, as well as providing for the making of parallel mortises or slots at desired transverse positions with respect to the stile, board or other object.

A further object is the provision of such a device which can be conveniently used instead of the ordinary brace and bit, or the like, with a considerable saving in labor and time, and not only enabling the work to be done with ease and dispatch, but also with accuracy and neatness, to comply with the various conditions required, the device being especially useful for mortising window frames or stiles for the reception of the sash cord pulleys.

The invention has for another object the provision of such a device having novel features of construction and arrangement of the component parts, to enhance the efficiency and utility of the device.

With the foregoing and other objects in view, which will be apparent as the description proceeds, the invention resides in the construction and arrangement of parts, as hereinafter described and claimed, it be-

ing understood that changes can be made within the scope of what is claimed, without departing from the spirit of the invention.

The invention is illustrated in the accompanying drawings, wherein:

Figure 1 is a side elevation of the device, with the driving mechanism removed.

Fig. 2 is a plan view thereof.

Fig. 3 is a section on the line 3—3 of Fig. 1 showing the driving mechanism applied.

Figs. 4 and 5 are sectional details taken on the respective section lines 4—4 and 5—5 of Fig. 1.

Fig. 6 is a longitudinal section of the stile or board, taken on the line 6—6 of Fig. 3, to show the work done by the device.

The device comprises a base 7 to seat on a table or other support, and may be secured in place, if desired, by any suitable means. A plate or member 10 is fitted for turning movement on the base 7 about a pivot bolt or screw 11 extending through said plate and threaded into the base, and also serving to clamp said plate on the base. The plate 10 has an upright flange or guide portion 12 which can be set in different vertical planes by turning the plate 10 when the screw 11 is loosened. The outer side of the flange 12 is provided with a horizontal longitudinal dove-tailed channel 13 in which a slide or work holder 14 of similar cross-section is movable. Wear strips 15 are disposed between the upper and lower edges of the slide 14 and the upper and lower bevelled undercut walls of the channel 13, for snugly guiding the slide 14 for reciprocatory movements, and screws 16 are threaded through the upper edge of the flange 12 to contact with the upper strip 15, for taking up wear. Lock nuts 16' are threaded on the adjusting screws 16 to hold them against accidental loosening.

In order to conveniently move the slide or work holder 14, a hand lever 17 is fulcrumed on a pivot screw 18 secured in the flange 12 at the rear and near one end thereof, and said lever extends upwardly and has a longitudinal slot 20 receiving a pin 19 secured to and extending rearwardly from the slide 14, the flange 12 having a slot 22 extending longitudinally thereof through which the pin 19 projects. The slide or work holder 14 is thus easily slid longitudinally by swinging the lever 17 by hand.

A length gage is provided for limiting the sliding movement of the slide 14, and includes a stop 21 secured by means of a screw 21' or the like to the outer side of the slide 14 at the upper edge thereof and overlapping the flange or guide 12 above the channel 13. Said stop 21 is movable between a pair of stops 23 depending from the opposite ends of overlapping slotted bars 23' secured on the upper edge of the flange or guide 12 by means of screws 23'' which extend through the slots of said bars. When the screws are loosened, the bars 23' can be adjusted longitudinally to position the stops 23 according to the desired adjustment, for determining the length of the mortise or slot. The flange or guide 12 is preferably graduated, as at 21'', to assist in positioning the stops 23.

20 A depth slide 24 is mounted for movement toward and away from the object and the base 7. Thus, said slide 24 has sleeves 27' slidable on rods 25 carried by and extending horizontally from the base 7 below the guide 12 and slide 14.

A depth gage is provided for limiting the movement of the slide 24 on the rods 25 toward the base 7 and object, to thereby determine the depth of a mortise. This gage includes a rod 33' secured to and extending from the base 7 at one end thereof adjacent to and parallel with one of the rods 25, and a stop arm 33 mounted on said rod 33' for sliding and turning movements. The arm 33 has a handle 35 for swinging it, to move said arm against the corresponding rod 25, as seen in dotted lines in Fig. 1, or to swing said arm away from said rod 25, as seen in full lines in said Fig. 1. An adjusting collar 34 is slidable on the rod 33' and is secured in place by means of a set screw 34' carried by the collar, and said collar can be readily adjusted to position the stop arm 33 and limit the movement thereof on the rod 33' toward the base. When the arm 33 is swung away from the corresponding rod 25, the slide 24 can move up to the base 7, but when said arm 33 is swung against said rod 25, it will stop the movement of the slide 24 at a predetermined position, to thereby limit the depth of the mortise accordingly.

The slide or member 24 has a guide or slideway 27 arranged vertically and rising perpendicularly from the lower edge portion of said slide between the ends of said slide, and a slide or block 40 is slidable upwardly and downwardly in said guide or slot 27, and has a circular opening or bore 28 extending therethrough transversely of the slide 24 and guide 27. The slide 40 has a clamping plate 40' at one side held by a clamping bolt 40'' to clamp said slide in its adjusted position.

The auger bit 43 or equivalent tool is rotated by a driving or operating mechanism

which is assembled with the slide 40. As shown in Fig. 3, the flexible operating mechanism, as disclosed in the aforesaid application, is used, and only the freely movable terminal portion of such mechanism is 70 shown (the same reference characters being used as in such application). Such mechanism includes a terminal yoke 26 which has bushings 36 and 36' secured to the terminals thereof, and a tubular spindle or arbor 37 is 75 fitted for rotation in said bushings. A pulley wheel 42 is secured on the spindle 37 between said bushings for retaining the spindle in place, and a belt 44 passes around said pulley wheel for rotating said spindle, and 80 is guided between rollers 45. The shaft or shank 38 which carries the bit or tool 43 is received by the tubular spindle 37, and said spindle has a screw-threaded portion 37' at that end opposite to the bit into which the 85 screw-threaded terminal 38' of the shaft 38 is secured, for fastening said shaft to the spindle. The shaft has a collar 38' thereon to bear against that end of the spindle opposite to the screw-threaded end, for fastening the shaft securely to the spindle, and the bit or tool 43 projects beyond the collar 38'. The bushing 36 is extended from the yoke 26 in order to enter the opening 28 of the slide or block 40, so as to provide a detachable slip connection between the driving mechanism and the portable or movable device. The extended portion of the bushing 36 is conveniently slipped in the opening 28, 90 for assembling the mechanism and device, and in order to hold them assembled, said bushing has an annular groove 39 in the extended portion thereof to receive a ball or catch 41 slidable in the slide or block 40 and projected by a spring 41' confined behind said ball. When the slide 40 and bushing 36 are fitted together, the ball or catch 41 is pressed into the bore or socket, and when the parts are moved together, said ball will snap into the groove 39, thereby holding the yoke 26 and slide 40 together, but permitting said parts to turn relatively, when the device is moved longitudinally. The bushing 36 can thus turn in the slide 40. When the driving mechanism and device are thus assembled, the bit or tool can be attached by sliding the shaft 38 into the spindle 37 and screwing said shaft into place. The bit is thus secured to the rotary spindle 37 of the driving mechanism, and such spindle and bit will be adjusted with the slide 40 upwardly and downwardly. The terminal portion or bushing 36 of the driving mechanism is thus conveniently assembled with the device for adjustment 100 therewith, to position the bit or tool accordingly, and in a like manner other devices or attachments can be used interchangeably with the mortising device, by having such devices each equipped with a 105

115

120

125

130

slide or block 40 to fit on the bushing 36. Various devices or attachments for doing different kinds of work can thus be used interchangeably with the driving mechanism.

5 A gage is provided for readily determining the transverse positions of the mortises or slots in the stiles or other objects. Thus, the slide or member 24 has a slot 50 extending parallel with the guide 27 at one side 10 of the slot thereof, and bolts or stems 51 are disposed in the slot 50 for longitudinal adjustment in said slot to different positions, and have stops or heads 52 for the contact of the block or slide 40 to limit the upward 15 and downward movement thereof. Nuts 53 are threaded on the bolts or stems 51 for clamping the stops 52 in their desired adjustments, and graduations 54 can be provided along the slot 50 for conveniently positioning the stops 52. Thus, when the bolt 20 40" of the slide 40 is loosened, said slide can be readily moved from one position against one stop 52 to the other position against the other stop 52, and said stops thereby enable 25 the position of the slide or block 40 to be changed quickly, for cutting parallel mortises or slots. By adjusting the stops 52, the transverse positions of the mortises or slots with respect to the object can be adjusted, 30 to space the mortises or slots the desired distances from the edges of the object and from one another.

The slide or work holder 14 has an opening 60 extending from one side to the other, 35 to accommodate the auger bit 43 in the different positions of said bit and slide, and said slide has vertical openings or slots 61 in the ends thereof for the reception of the window frame stile 62, board or other object which is inserted on edge into the slide, 40 as seen in Fig. 3.

A work clamp is carried by the slide or holder 14 and includes a stub shaft 63 mounted for turning movement in one end 45 portion of the slide 14 and having a cam 64 working within a slot 65 in said slide to bear against the stile or board 62, and clamp same against the back of the slide or holder 14. A hand lever 62 is secured to the shaft 63, 50 and when raised will turn the cam 64 to bind the object in place.

In using the device, the slide or block 40 is assembled with the driving mechanism, by fitting the bushing 36 in said slide, and the ball 41 will snap into the groove 39, to hold the mechanism and device assembled. The bit or tool 43 is then attached by inserting the shaft or stem 38 thereof into the tubular spindle 37 and screwing said shaft into 55 place with the spindle. The stile or board 62 is then inserted into the slide or holder 14, the bit 43 being retracted, and said stile or board is clamped in said slide or holder 60 swinging the hand lever or arm 66. The stile or board is thereby securely held in po-

sition, for movement with the slide 14, and the stops 23 are adjusted to limit the longitudinal movement of the slide 14 and object. The collar 34 is then adjusted to the desired position, so that when the stop arm 33 is 70 swung against the corresponding rod 25, the slide 24 is limited in its movement toward the work, when a shallow mortise is desired, or one which does not extend through the stile or board. The stops 52 are set to determine the upper and lower positions of the auger bit 43. Then, by clamping the slide or block 40 in one position against the corresponding stop 52, and after swinging the stop arm 33 to position against the corresponding rod 25, the slide 24 is moved toward the work, thereby presenting the bit 43 to the face of the stile or board 62, and by swinging the lever 17, the slide 14 and stile 62 are slid longitudinally, for cutting 80 or routing a mortise in the stile at the desired transverse position and of the predetermined depth and length. The depth of the mortise is determined by the position of the stop arm 33, and the length of the 85 mortise by the stops 23. By swinging the stop arm 33 out of the way of the slide 24, the bit 43 can now be moved further into the stile 62, to pass entirely through the stile, and the slide 14 is then moved so that the bit 90 cuts a slot 67 in the stile, but the slide 14 is not moved sufficiently to bring the stop 21 against the stops 23, thereby making the slot 67 of shorter length than the shallow 95 mortise 68. The mortise thus formed provides a slot 67 through the stile or board, with shallow portions beyond the ends of such slot, for receiving the housing of a sash cord pulley used on window frames, as 100 well known.

By loosening the block or slide 40 and bringing same against the other stop 52, a parallel mortise of the same kind can then be cut in the stile or board.

Various sizes and positions of mortises 110 can thus be produced, which is especially useful for making the pulley mortises of window frames, and bits 43 of different diameters can be used interchangeably, for making mortises of different widths. The 115 lengths and depths, and also the transverse positions of the mortises can be readily determined by the gages and adjustments provided. Furthermore, by loosening the screws 120 11 and turning the plate or member 10, the slide 14 and object can be positioned either at right angles or at an acute or obtuse angle with the bit 43, to make the end walls of the mortises either at right or other angles with the sides of the objects.

The work can be done quickly and easily, without the labor and time required as when doing the work with an ordinary brace and bit. Furthermore, the work is done accurately and neatly, and without a possibility of 130

spoiling the job, because the adjustments made will define and limit the movement of the bit or cutter.

Having thus described the invention, what is claimed as new is:—

1. A device for mortising and slotting stiles and other boards comprising a work holder having a longitudinal opening for receiving a stile or board by a longitudinal movement and having an opening at one side to expose one side of the stile or board, means carried by the work holder for clamping the stile or board therein, a member having a slidable connection with the work holder, a slide supported from said member for movement toward and away from the work holder, another slide supported from the aforesaid slide for adjustment transversely of the stile or bar, and an auger bit carried by the last named slide to work within the second named opening of the work holder and to operate on the stile or board from one side thereof between the edges thereof.
2. A device for mortising and slotting stiles and boards comprising a work holder having a longitudinal opening for receiving a stile or board and having an opening at one side for exposing one side of the stile or board to be operated on, means carried by the work holder for clamping the stile or board therein, a member having a sliding connection with the work holder, guiding means carried by said member including a pair of rods extending beyond the work holder, a slide movable on said rods and having a guide between the rods extending transversely of the work holder to be disposed transversely across said side of the stile or board, a slide movable in said guide, and an auger bit carried by the second named slide to operate on the stile or board from said side thereof within the second named opening of the work holder, between the edges of the stile or board.
3. A mortising device comprising a work holder, a member having a sliding engagement with said member, a second member pivotally connected with said member to be positioned at different angles relatively to the work holder, guiding means extending from the second named member beyond the work holder, a slide movable on said guid-

ing means toward and away from the work holder, and a slide carried by the aforesaid slide for adjustment transversely of the work holder and adapted to carry an auger bit to operate on the object held by the work holder.

4. A mortising device comprising a plate having a flange extending at an angle therefrom, a work holder having a sliding engagement with said flange at one side thereof, a member bearing against said plate and having a pivotal connection therewith for the adjustment of said member and work holder to different angles relatively to one another, guiding means carried by said member extending beyond said flange and work holder, a slide movable on said guiding means and having a guide extending transversely of and across one side of the work holder, and a slide adjustable in said guide for carrying an auger bit to operate on the object held by the work holder.

5. A mortising device comprising a base member, a work holder having an adjustable connection therewith, a pair of rods extending from the base beyond the work holder, a slide movable on the rods and having a guide between the rods disposed transversely of the work holder, and a slide adjustable in said guide for carrying an auger bit to operate on an object held in said holder.

6. A mortising device comprising a plate having a flange extending therefrom in one direction, a work holder having a sliding connection with said flange at one side thereof, a base on which said plate is fitted and having a pivotal connection therewith, a slide having a sliding connection with said base to move toward and away from the work holder and having a guide extending in the same direction as the flange to extend across one side of an object in said work holder, and a slide adjustable in said guide for carrying an auger bit to operate on said object.

In testimony whereof I have signed my name to this specification in the presence of two subscribing witnesses.
